UNITED STATES PATENT OFFICE.

ALLEN N. MERRILL, OF BATAVIA, ILLINOIS.

FARMER'S BOILER.

Specification forming part of Letters Patent No. 98,988, dated January 18, 1870; reissue No 4,062, dated July 5, 1870.

To all whom it may concern:

Be it known that I, ALLEN N. MERRILL, of Batavia, in the county of Kane and State of Illinois, have invented a new and useful Improvement in Farmers' Boilers, of which the following is a specification, reference being had to the accompanying drawings, which form a part thereof.

The object of my invention is to make a cheap, durable, and portable boiler for farmers to use for cooking feed for stock; and the nature of the invention consists in providing the top of the fire-pot with projections or supports for supporting the kettle, so that it will rest upon the fire-pot and not upon the case; and it further consists in the combination of the various parts, hereafter specified, to make a compact, portable boiler.

Figure 1 is a perspective view of the entire boiler; Fig. 2, a transverse vertical section; Fig. 3, a perspective view of the kettle; Fig. 4, a perspective view of the fire-pot; and Fig. 5, a perspective view of the feed-spout.

A is the bottom piece of the boiler; B, a conical casting, forming an ash-space beneath the fire-pot; C, the fire-pot, resting upon the conical casting B, as shown, in which there is a grate, c. The fire-pot is made with an opening, O, on one side for the admission of coal, and it has at its top projections or supports 2 upon which the kettle H rests. H may be an ordinary kettle, or there may be a pipe, 4, extending from the bottom of the kettle to carry off the contents thereof if desired. The stopper d may be used to close the pipe. E is a jacket, surrounding the kettle in such a way as

to make a space between the jacket and kettle for the heat to pass around the kettle. G is the smoke-pipe. D is an inverted cone resting on the fire-pot, and makes a support for the jacket or case E. 3 is a fuel-spout, which is made in one piece, as shown in Fig. 5, and secured to the fire-pot and boiler, as shown. It has a cover, b.

By this arrangement coal can be fed into the coal-pot by simply removing the cover b. The draft to the fire is through the base cone B of the boiler.

I have a light conical fire pot, requiring no fire-brick, with a grate at its base that can be shaken and damped, the ashes falling into an ash-pit beneath. The conical shape of the fire-pot causes the coal, that is conveniently fed therein through the feed-spout by simply removing the cover, to fall upon the fire-grate in a small space, and the projections 2 support the kettle, making it firm upon the fire-pot. It is a light portable boiler, readily managed in every particular.

I claim—

1. Providing the fire-pot C with the projections or supports 2, for the purpose of supporting the kettle, substantially as set forth.
2. The conical base B, conical fire-pot C, provided with projections 2, the fire-grate c, cone D, jacket E, and kettle H, when constructed and operating substantially as described and shown.

ALLEN N. MERRILL.
